ELECTRIC DISCHARGE DEVICE AND
ELECTRODE THEREFOR

Lyman B. Johnson, Cleveland Heights, Ohio, assignor to General Electric Company, a corporation of New York

Application November 27, 1941, Serial No. 420,638

8 Claims. (Cl. 176—122)

This invention relates to electric discharge devices, and is useful in devices producing radiation for various purposes, such as germicidal and therapeutic ultra-violet lamps and tubes, and lamps or tubes used industrially for irradiating or treating various substances and products, or for blueprinting and other photographic purposes, as well as lamps or tubes for more ordinary illumination. Speaking in a general way, the invention aims at improvement of electric discharge devices as regards blackening of envelope walls and wastage of electrodes or cathodes, as well as at obviating the necessity of activating such electrodes with special electron-emissive materials. This application is a continuation-in-part of my application Serial No. 381,633, filed March 4, 1941, now U. S. Patent No. 2,313,646, granted March 9, 1943, as to certain features disclosed therein. In the case of discharge devices operating on alternating current, the invention is applicable to both the cooperating electrodes, since they function as cathode and anode alternately.

Discharge devices in which a discharge is passed between electrodes in an ionizable atmosphere have come into wide use in recent years. Generally, these devices have a metal vapor (such as that of mercury) as the operating atmosphere, and also include an inert auxiliary or starting gas (such as one of the rare gases) at pressures up to several millimeters. Lamps of this character are classified in two groups or types, according to the pressure of the mercury vapor. In the low-pressure group, represented for example by the well-known Cooper Hewitt lamps, the devices operate at a relatively low temperature, and consequently at very low pressure. The discharge at such low pressures characteristically spreads out into a uniform glow which fills the entire tube. In the high-pressure field, of which U. S. Patent No. 2,202,199 to Germer is representative, the lamp is allowed to heat considerably, and the pressures may build up to very high values, ranging anywhere from a fraction of an atmosphere to many atmospheres. As such pressures, the arc is characteristically constricted into a narrow cord. The dividing line between the two types may be taken as the pressure at which the discharge begins to contract; and this is in practice determined by the size of the envelope and its consequent temperature during operation. While the division of types is not well defined, it does occur somewhere between several hundred millimeters and about one atmosphere.

One of the chief problems in the design of discharge devices of either type for a reasonably long useful life has been the construction of electrodes which do not disintegrate under bombardment to which they are necessarily subjected by the current carriers in the arc. This bombardment is caused principally by positive gas ions which are accelerated to high velocities by the so-called cathode fall. Unless preventive measures are taken, such ions attain sufficient velocity to knock minute particles of metal or of activating coating from a cathode. This phenomenon results in a gradual disintegration and final destruction of the cathode, as well as a blackening of the tube wall upon which the particles collect.

The destructive effect upon the cathode is particularly prevalent during the starting period of the lamp: i. e., the period of time before the cathode has attained proper emission temperature, including, in the case of the high pressure lamp, the time before the heating of the lamp has built up an atmospheric pressure of full operating value. The destructive effect of bombardment during starting on an activated cathode is enhanced by a tendency of the cathode spot of the arc to jump around on the surface of the cathode, as if in an attempt to find highly activated areas. During the starting period, a relatively high potential-fall exists in the neighborhood of the cold cathode, so that the positive ions that strike the cathode have much more energy, and produce more sputtering; and as the pressure (even in the high-pressure type of lamp) is low at this time, there are relatively few gas particles to be in collision with the sputtered material from the cathode, and thereby reduce the actual net loss of material by sputtering. On the other hand, when the cathode is at proper emission temperature, the cathode fall is greatly reduced; and when the gas pressure (in the high pressure case) is at normal operating value, the cathode is blanketed by gas particles which repel sputtered particles of metal back to the cathode. After starting is over, therefore, positive ions do not so greatly damage the cathode when they strike it.

The destructive and blackening effect of cathode bombardment has been so great that it has hitherto proved impossible to construct a commercially successful discharge lamp with bare or unactivated electrodes; for about the only practicable way to avoid or reduce the deleterious effects of bombardment has been to provide the

cathode with so-called activating material—that is, material which when heated emits electrons much more copiously than does the cathode metal itself—thus reducing the cathode fall and the energy of the bombarding positive ions. Examples of activators are certain metallic oxides, or materials which break down to form the oxides when heated, such as barium or strontium carbonates or hydroxides. In many cases, also, there is considerable difficulty in getting the discharge to start between electrodes without activation.

The activation method of obviating destructive cathode bombardment has various disadvantages, however. In the first place, it is necessary to provide a tough binder to insure that activating oxides shall adhere properly to the cathode. It is also generally necessary to subject the activating materials to some sort of an activation process before they are in proper condition for emission. All this adds to the technical difficulties and cost of manufacture. Activating coatings on a cathode tend to flake off during the life of the cathode, which in itself adds to the blackening of the discharge envelope. Furthermore, activating material from an electrode deposits on the envelope wall over a great distance from its ends; and after initially depositing on the walls, it tends to migrate or spread toward the center of the envelope, thus increasing the obscuration. Moreover, some of the usual activating materials, such as compounds of the alkaline earth metals, have a tendency to initiate devitrification of a quartz or glass envelope.

I have discovered a way of keeping down or reducing the deterioration or loss of material of discharge electrodes, and the blackening or obscuration of the associated discharge envelopes, without necessity for activating material on or in the electrodes, or for the employment of auxiliary gas of specially high pressure, as referred to in my pending application above identified, and without any real difficulty in starting the discharge. The invention is not only applicable to discharge devices of the type disclosed in my aforementioned application, but also to devices employing working substances and pressures other than there referred to.

In accordance with my invention, I have found that wastage of a bare refractory metal electrode and blackening of the associated envelope wall can be reduced or minimized, without necessity for activation, by a suitable temperature of the electrode or its portion from which the discharge or arc takes off. This temperature must be high enough to assure the requisite emission of electrons to reduce the cathode fall and obviate serious sputtering—just what has heretofore been achieved by activation—yet low enough to prevent undue evaporation of the refractory metal, which would produce blackening as serious as that from sputtering. Evaporation of the refractory electrode metal has not been a factor in the operation of activated electrodes, because the profuse electron emission from activating materials rendered it quite needless to approach operating temperatures of the metal at which evaporation would be appreciable. The optimum temperature for my purpose is that at which the combined sputtering and vaporization losses are substantially minimized, which for tungsten is substantially of the order of some 2700–3200° K., and even a little lower and higher than this range, at the electrode area or portion from which the discharge actually takes off.

In the case of a "self-heating" electrode, the

heat to maintain it or its arcing portion at the desired operating temperature must, of course, come from the action of the discharge or arc. This is practicable, I find, if the electrode body is a part of limited mass which can be heated rather uniformly, at least in starting, so that enough of it contributes to the emission of electrons without any of it ever being seriously overheated. Accordingly, the electrode body should be fairly compact and stubby, so that the heat generated where the discharge takes off may be rather uniformly distributed over a blunt arcing end of said electrode body. To assure that the arc shall properly heat the electrode, taking off of the discharge from the connector, rather than from the electrode body, is prevented. Of course the energy supplied the electrodes through the lamp leads has to provide all the heat that is lost from an electrode arcing end or area whence the discharge takes off, by conduction and radiation to and from the rest of the electrode and its current lead and support—as well as the rest of the energy represented by the arc or discharge phenomena—so that the heating and the heat losses balance at the desired operating temperature of said area.

In order to prevent or control electrode wastage and envelope blackening, I not only maintain the electrode (or at least its arcing portion or area where the discharge takes off) at suitable temperature during the running of the discharge device, but I provide for heating up the electrode body or its arcing portion to a suitable operating temperature, during starting, before appreciable sputtering can occur. I have discovered that both rapid heating up and subsequent temperature maintenance can be assured by artificially reducing the thermal conduction of the electric current connector, as by increasing its length beyond what is otherwise needful. When the connector is made of such limited thermal conduction that in running the heat loss from the arcing portion balances the heating thereof from the discharge at an operating temperature where sputtering losses are kept down without incurring serious losses by evaporation of metal—or, at the optimum, combined sputtering and vaporization losses are substantially minimized—it is found that the electrode (or its arcing portion) will heat up before important sputtering occurs if the electrode is made of low heat capacity or thermal inertia; in other words, sufficiently small. Conversely, if the electrode is made sufficiently small to heat up rapidly, it will also be small enough to be heated sufficiently uniformly by the discharge during running.

In a word, then, the mass and thermal capacity of the electrode and the thermal conduction of the connector are correlated, for both starting and running, to control the temperature of the electrode and its arcing portion, and the value of the cathode fall. It follows that the electrode should be designed and proportioned according to the current in the discharge which it is intended to transmit, and by which it is heated; and any serious deviation from the rated discharge current, in service, will result in either sputtering or evaporation of electrode metal, with consequent blackening of the discharge envelope, because of the consequent underheating or overheating of the electrode to an operating temperature outside the above-indicated range.

In order to secure easy starting of the discharge without activation of the electrodes, I combine 75 with their other features above set forth a rough-

ened arcing surface. This, I find, greatly reduces the voltage necessary for starting. Such roughness of the electrode surface may consist of grooving formed in a variety of ways, or may reside in the texture of the refractory metal of the electrode. The rough character of the electrode surface is also helpful for assuring that the discharge shall operate from the electrode body to the virtual exclusion of its connector.

During normal running of my device, after a stable condition has been reached, the pressure of the operating atmosphere of mercury or the like influences electrode wastage and envelope blackening, because it affects the temperature of the electrode and its arcing portion or area from which the discharge takes off. The higher the operating pressure in the lamp, the more constricted is the arc and the smaller the effective arcing portion or area, and the greater is the heat loss by conduction from the electrode to the discharge atmosphere. Moreover, the temperature of the arcing portion is affected by conduction to the rest of the electrode body, which does not attain so high a temperature as when the arc spreads out over it and so acts to heat it all over directly. Hence the electrode temperature is in some measure a function of the working pressure in the discharge envelope. While small differences in pressure may not be of any great importance, it may be desirable to take account of very large pressure differences in designing the electrode.

Pressure of the starting gas is favorable to the suppression of electrode wastage and envelope blackening during the starting period of a discharge device embodying my invention; but it is by no means a major factor, as in the lamp set forth in my aforementioned application.

Various features and advantages of the invention besides those already referred to will appear from the following description of species and forms of embodiment, and from the drawing.

In the drawing, Fig. 1 is a tilted or perspective view of a discharge device or lamp embodying my invention, with a wiring diagram of suitable electric circuit connections; and Figs. 2 and 3 show axial sections through the ends of this lamp, on a larger scale than Fig. 1.

Figs. 4 and 5 are views generally similar to Figs. 2 and 3 illustrating a somewhat different conformation of the ends of the discharge envelope.

Fig. 6 shows characteristic curves of current-voltage and arcing tip temperature for a discharge device embodying my invention.

As shown in Fig. 1 of the drawing, the discharge device is a lamp having a vitreous elongated or tubular envelope 10, of quartz or glass, for example, provided with solid operating electrodes 11, 11 in its opposite ends, and permeable to ultraviolet and visible radiation. In the present instance, there is also a solid auxiliary starting electrode 12 in one end of the envelope 10, closely adjacent the corresponding operating or main electrode 11. A charge of vaporizable and ionizable working substance, such as mercury, is indicated by a droplet 13 inside the envelope 10. The charge 13 may either be greater in amount than will vaporize under the heat of the lamp, so that an unvaporized surplus will always remain, assuring operation of the device with an atmosphere of saturated vapor, or the charge 13 may be less than required to afford such an unvaporized surplus, so that the lamp will operate with an unsaturated atmosphere. The envelope 10 also con-

tains an atmosphere of starting gas such as one or more of the rare gases like argon, krypton, xenon, etc. For the device hereinafter described, having the proportions stated, argon at a pressure of 20 mm. of mercury is satisfactory. The proportions chosen may preferably represent a constriction of the envelope 10 such as results in a discharge-constricting pressure therein during normal operation.

As shown in Figs. 1, 2, and 3, the envelope 10 is a straight, uniform tube with molded ends 14, 14 slightly reduced around the electrodes 11, 11 and with flat end walls from which greatly reduced end chambers or necks 15, 15 project around the main inleads 16, 16 and the auxiliary inlead 17, these necks 15, 15 embodying graded seals. This is a well-known form of construction for therapeutic tubes, and hence need not be more particularly described.

The electrodes 11, 11 and 12 are shown unactivated, consisting merely of bare refractory metal like tungsten. The auxiliary starting electrode 12 is shown as of an ordinary type, comprising a simple straight piece of refractory metal wire. The discharge normally operates between proximate arcing portions or tips 20, 20 at the inner ends of the electrode bodies 11, 11. As a matter of practical construction, the internal current connectors of the lamp are divided, each of them consisting partly of an inlead 16 and partly of another connector wire 21 to which the electrode bodies 11, 11 are attached. Each inlead 16 and wire 21 are joined together by a telescopic joint at 22.

The electrodes 11, 11 (which may be counterparts of one another) are of relatively small mass and of low heat-capacity in proportion to the discharge current—as compared with solid self-heating electrodes heretofore used—so that the heat which each electrode absorbs from the discharge during starting suffices to bring it to operating temperature before appreciable sputtering can occur, and without local overheating. In other words, very rapid heating of the electrode 11 produces a correspondingly rapid decay of the cathode fall below the value at which tungsten sputters seriously. Here two factors are involved: the rate of heat supply by the discharge, and the rate of absorption and distribution of this heat throughout the mass of the electrode 11. Though small in total mass, the electrode 11 is shown relatively compact, or stubby, so that the heat which any part of its area receives directly from the discharge is rapidly distributed to its whole mass. This compactness is apparent in Figs. 1 and 3, as contrasted with the lack of compactness of the mass of the auxiliary electrode 12; the latter might have its end fused without its portions behind reaching any very high temperature. A helical construction for the electrode 11 is here illustrated, and will presently be described.

Behind the electrodes 11, 11, as already indicated, are the internal connectors of the lamp (each here shown as comprising a connective part 21, as well as an inlead 16) which conduct the discharge current to the electrodes, and also conduct heat away from the electrodes to the envelope 10, but which do not normally take the discharge or arc, unless quite briefly in starting. As here shown, the wires forming each connector are of a thickness or diameter reasonably commensurate with the over-all diameter of the electrode 11 itself, though smaller. This thickness of the connector assures that the arc will

not take off from it to the exclusion of the electrode 11. But while the connector is thus decidedly stout or thick-set as a mere matter of cross-section, this is compensated by extra effective length, so that the actual, effective heat conduction is relatively low. To provide this extra length, a loosely coiled helical form for the connective part 21 is here illustrated, and will presently be described. However, the important point is not any particular means of securing low heat conduction, but rather the thing for which low heat conduction is the means. Indeed, a fine wire connector without coiling may be used, if surrounded with suitable insulation to prevent the discharge from taking off therefrom.

The low thermal conduction of the connector formed by the connective part 21 and the lead 16 is determined by two considerations: control of the conduction of heat away from the electrode 11 during running on the one hand, and during starting on the other. During running, the loss of heat from the arcing portion 28 must balance the heating thereof by the discharge at an operating temperature for the portion 28 at which combined sputtering and vaporization losses are reasonably kept down or minimized; otherwise, the lamp would blacken badly during running. (In devices with activated electrodes, this condition has not been reached, because the activation supplied electrons to prevent sputtering at temperatures well below that at which vaporization could become serious.) During starting, the loss of heat from the electrode 11 must be so far overbalanced by the heating from the discharge that the electrode actually heats up to operating temperature before appreciable sputtering can occur.

As here shown, each electrode 11 and conductor 21 consists structurally of a single helically coiled refractory wire. Besides close turns forming the electrode 11 and loose, open turns forming the connective part 21, this coil includes several rearmost close turns 22 forming a socket that engages around the current lead 16 to make a telescopic joint. Actually, the arc may sometimes take off initially from the part 22, especially when a new lamp is started for the very first time. In addition to end turns of the coiled wire, the electrode 11 may include a heat-distributor in the form of a short wire insert plug 25 filling these turns. Preferably this piece 25 is soundly welded to the helical turns that it occupies, especially the outer end turn, and this turn and the piece 25 may be ground off flush to provide an even end face for the tip 28. The rear socket coils 22 may also be attached by welding to the lead end 16 around which they fit.

Making the coils forming the electrode 11 and the connective part 21 separate from the lead 16 greatly facilitates construction, since it allows of winding wire in a continuous coil whose pitch is suitably varied, and simply cutting this coil into sections each consisting of the desired turns to form an electrode and connector device. Functionally, however, it will be understood that the coil turns 20, 21 and the straight lead wire 18 might equally well be one continuous length of wire, without anything corresponding to the socket turns 22, 22.

The construction shown in Figs. 4 and 5 differs from that of Figs. 1, 2 and 3 in having the molded tube ends 14a, 14a around the electrodes 11, 11 smaller than the tube ends 14, 14 in Figs. 1-3. Otherwise, this device corresponds essen-

tially to that in Figs. 1-3, and its corresponding parts and features are marked with the same reference characters.

Illustrative circuit connections for the starting and running of the discharge device are shown in Fig. 1 as including a high-leakage-reactance transformer T of semi-auto type with its primary connected across an A. C. power supply circuit P and with its secondaries t1, t2 connected in series across the main discharge electrodes 11, 11. Through a high current-limiting resistance R and a thermal (bimetallic) switch S, one of the main electrodes 11 and the associated auxiliary starting electrode 12 are connected across the transformer secondaries t1, t2 in parallel with the electrodes 11, 11. The heating resistor r of the thermal switch S is shown connected in one side of the secondary circuit to the main electrodes 11, 11, so as to be heated whenever the arc operates. For a discharge device intended to run on a voltage of 225 volts, the transformer T may be so chosen as to produce this voltage across its serially connected secondaries t1, t2 on open circuit, and to give a secondary current of about 3.8 amperes on short-circuit.

Under these conditions, energization of the circuit P will automatically start the auxiliary discharge across the short electrode gap 11, 12 and then the main discharge across the electrode gap 11, 11. Thereafter the thermal switch S will disconnect the auxiliary electrode 12 from the secondary circuit, so that the seal around the leads 16, 17 will not be injured by the D. C. voltage subsisting between them when both are in circuit; and this switch S will remain open at all times when current is on.

For the convenience of those desiring to practice my invention, I will now give specific construction data for lamps such as illustrated in Figs. 1-5 suitable for operation with a discharge current of about 3.0 amperes, the Figs. 1-3 device being suitable for an operating voltage of about 95 volts and the Figs. 4 and 5 device for about 135 volts. These lamps may be built with envelope tubes 18 of clear fused quartz about $\frac{5}{8}$ to $\frac{3}{4}$ inch in internal diameter, and with an electrode gap of $3\frac{1}{4}$ inches for the shorter tube of Figs. 1-3, or about $6\frac{1}{8}$ inches for the longer tube of Figs. 4 and 5. The reduced end chambers 14, 14 may each extend about $\frac{3}{8}$ inch axially of the envelope 18, with an internal diameter of about $\frac{1}{8}$ inch for Figs. 1-3, or $\frac{1}{4}$ inch for Figs. 4 and 5. The inleads 16, 16 and 17 may be of 30 mil molybdenum wire, extending into the necks 15, 15 to about the positions shown,—i. e., a distance of about $\frac{3}{4}$ inch for Figs. 1-3, or 1 inch for Figs. 4 and 5.

The coil forming each electrode 11 and its conductor 21 may be of 30 mil tungsten wire, and may be wound in a lathe on a mandrel wire of the same size, i. e., of 0.030 inch diameter. Each coil 11, 21, 22 may comprise three close turns 11 of 100 per cent pitch (33.3 T. P. I.), three loose-coiled, open turns 21 of 200 per cent pitch (16.7 T. P. I.), and three close turns 22 of 100 per cent pitch. In practice, it is advantageous to wind 3 close turns, 3 open turns, 6 close turns, 3 open turns, 6 close turns, etc., in alteration, and to cut through the middle of each group of 6 close turns to form the individual coils or electrode and connector devices. The heat distributor insert or plug 25 for each electrode 11 may consist of a piece of 30 mil tungsten wire 0.090 inch long, inserted into the three end turns 20

and electrically welded in place in a protective inert or reducing atmosphere. The three end turns 22 may be similarly welded in place on the inleads 16, 16, before sealing the latter into the glass of the end chambers 15, 15.

For lamps of higher wattages, appropriate enlargement of essential parts may be found desirable; e. g., a lamp for a discharge current of 6 amperes operating at 525 volts may have an envelope 10 of 1½ inch internal diameter, an electrode gap of 48 inches, and electrodes 11, 11 similar in essentials to those above described, except that the coils of 30-mil wire forming them may be wound on a 45-mil mandrel, their inserts 25 may be of this same size, and their inleads 16, 16 may also be of this same size.

It will be understood, of course, that the foregoing particulars are illustrative of suitable designs, and are not intended as defining or limiting my invention in its broader aspects; on the contrary, the proportions and forms of construction can be widely varied.

In operation, the discharge or arc prefers the compact electrode body 11, with its grooves formed by the close wire convolutions and the plug 25 in them, to the connective part 21 where the turns are opened up, or the socket 22; i. e., even when it starts on the part 22 or on the connective part 21, the discharge straightway shifts to the electrode 11. As regards the parts 11, 22, this is at once intelligible in view of their having about the same mass, since the electrode 11 affords a shorter arc path. It becomes intelligible as regards the parts 11, 21 when it is considered that the openness of the turns 24 makes them a mere length of plain, smooth wire, rather than a grooved or otherwise rough-surfaced body like the electrode 11. As already mentioned, the discharge prefers a rough surface, and starts more easily from such a surface than from a plain, smooth one. Such definite preference of the discharge for the electrode 11 and its tip 20 is important, since otherwise the heating effect of the discharge might be so dissipated over the parts 11, 21, 22, as the arc shifted from one part to another, that the electrode 11 would not be heated to adequate emissive temperature, and objectionable sputtering would occur.

While the discharge current is materially higher during the starting period than during the stable running condition after the device has fully heated up—because of the low voltage drop in the discharge under the low pressure existing in the discharge envelope 10 at starting—this does not entail material overheating of the electrode 11 or of its tip 20, because under the low pressure during starting the discharge spreads out over all or most of the surface of the electrode 11, heating it evenly and providing sufficient electron emission to lower the cathode fall and prevent sputtering during starting. As the mercury pressure in the envelope 10 increases above a value of several hundred millimeters and the device reaches a stable running condition, however, the discharge or arc contracts to occupy and heat directly only the end portion or tip 20, including the end turn of the electrode coil and the end of the plug 25, say. (In general, it is the temperature of this end portion that is hereinafter referred to as the operating temperature during running.) For example, observations made during normal, stabilized running on an electrode 11 constructed and proportioned as illustratively stated above in connection with Figs. 1—5 showed a falling off of temperature at the 75

rate of about 100° K. to 200° K. per wire turn from the tip 20 back to the connective part 21, corresponding to a reduction in emission per unit of area of as much as 90 per cent in the length of the first electrode turn that forms the tip 20, so that this first turn affords by far the major proportion of the electron emission from the electrode.

Discharge devices with unactivated solid electrodes afford a variety of important advantages over those with activated electrodes. The electrode construction is simpler and less expensive, special manufacturing steps incident to activated electrodes are altogether avoided, and the operations of exhausting the lamp or the like are materially shortened. The warm-up time in starting the lamps can be made shorter, and changes in the starting voltage during their useful life do not occur. There is no active alkaline material of high vapor pressure to be sputtered or vaporized on to the envelope walls, and hence no devitrification or other deterioration of the walls by such material. On the contrary, the only material that can deposit on the walls by sputtering or vaporization is tungsten or other refractory metal of the electrodes, which is unreactive toward the vitreous material, deposits only on the very ends of the envelope tube, close to the electrodes, and does not migrate along the tube toward its middle after it deposits, as do the ordinary activating materials. Accordingly, the radiant output of the tube is better maintained during its life, both in the luminous range and in the ultraviolet.

The characteristic of my discharge device with unactivated electrodes differs essentially from that of lamps having activated electrodes; viz., the lamp voltage is dependent on the discharge current, and increases as the current is reduced, as by a resistor or the like in series with the lamp. This increase in lamp voltage with reduction in current is due to a rapid reduction of the average electrode temperature and of the thermionic electron emission as the discharge current which heats the electrode is reduced. Corresponding current-voltage and arcing tip temperature curves for the lamp of Figs. 1—3 are shown in Fig. 6, from which it will be seen that as the discharge current is increased, the discharge voltage approaches an asymptotic minimum. The electrode temperature is very much higher in relation to the current than for an activated electrode, corresponding to the lower emission of electrons from electrode metal as compared with that from activating materials.

In studying the characteristics of an electrode design, curves such as shown in Fig. 6 should be plotted from a device embodying a pair of the electrodes and having an unsaturated atmosphere of mercury vapor in the range covered by the curves, in order to obviate masking of the electrode characteristics by effects arising from condensation and vaporization of mercury.

What I claim as new and desire to secure by Letters Patent of the United States is:

1. An electric discharge device of the high-pressure type comprising a radiation-transmitting envelope containing vaporizable and ionizable metal and starting gas, together with co-operating widely spaced electrodes in said envelope which are provided with current lead connections from its exterior, and one of which, functioning alternately as anode and as cathode, is an unactivated stubby compact refractory metal body pre-

senting to the discharge a solid center and a blunt arcing end throughout which the high heat from the discharge is distributed by the compactly concentrated metal, while the total exposed electrode surface is so correlated with the rated discharge current through the electrode, and with the operating pressure of the discharge atmosphere, that the heating of said arcing end by the discharge and the cooling thereof by conduction and radiation to and from the rest of the electrode and its current lead and support are in balance for a temperature of said arcing end that is of the order of 3000° K.

2. An electric discharge device of the high-pressure type comprising a radiation-transmitting envelope containing vaporizable and ionizable metal and starting gas, together with co-operating widely spaced electrodes in said envelope which are provided with current lead connections from its exterior, and at least one of which is a cold-starting, self-heating electrode functioning alternately as anode and as cathode, and is an unactivated rough, stubby, compact, refractory metal body presenting to the discharge a solid center and a blunt arcing end throughout which the high heat from the discharge is distributed by the compactly concentrated metal, thus producing a corresponding distribution of the discharge over said end, while the total exposed electrode surface is so correlated with the rated discharge current through the electrode, and with the operating pressure of the discharge atmosphere, that the heating of said arcing end by the discharge and the cooling thereof by conduction and radiation to and from the rest of the electrode and its current lead and support are in balance for a temperature of said arcing end that is of the order of 3000° K., said electrode, furthermore, being of such small total mass and thermal capacity that in starting its said arcing end heats up to a temperature of the order aforesaid before substantial sputtering of the refractory metal can occur; whereby wastage of said electrode and blackening of said envelope wall are prevented or minimized during both running and starting.

3. An electric discharge device of the high-pressure type comprising a radiation-transmitting envelope containing vaporizable and ionizable metal and starting gas, together with cooperating widely spaced electrodes in said envelope which are provided with current lead connections from its exterior, and at least one of which is a self-heating electrode functioning alternately as anode and as cathode, and is unactivated and consists of a coil of refractory metal wire and a refractory metal heat-distributing plug occupying and electrically and thermally interconnecting the adjacent convolutions of said coil, thus forming a rough, stubby compact body presenting to the discharge a blunt arcing end throughout which the high heat is distributed by the compactly concentrated metal, while the total exposed electrode surface is so correlated with the rated discharge current through the electrode, and with the operating pressure of the discharge atmosphere, that the heating of said arcing end by the discharge and the cooling thereof by conduction and radiation to and from the rest of the electrode and its current lead and support are in balance for a temperature of said arcing end that is of the order of 3000° K., said electrode, furthermore, being of such small total mass and thermal capacity that in starting its said arcing end heats up to a temperature of the order aforesaid before substantial sputtering of the refractory metal can

occur; whereby wastage of said electrode and blackening of said envelope wall are prevented or minimized during both running and starting.

4. An unactivated refractory tungsten electrode for functioning alternately as anode and as cathode in a long-gap high-pressure discharge, said electrode being a stubby compact body presenting to the discharge a solid center and a blunt arcing end throughout which the high heat from the discharge is distributed by the compactly concentrated metal, thus producing a corresponding distribution of the discharge over said end, while the total exposed electrode surface is so correlated with the rated discharge current through the electrode, and with the operating pressure of the discharge atmosphere, that the heating of said arcing end by the discharge and the cooling thereof by conduction and radiation to and from the rest of the electrode and its current lead and support are in balance for a temperature of said arcing end that is of the order of 3000° K., said electrode, furthermore, having a rough arcing surface and being of such small total mass and thermal capacity that in starting its said arcing end heats up to a temperature of the order aforesaid before substantial sputtering of the refractory metal can occur.

5. An unactivated refractory metal electrode for functioning in a long-gap high-pressure discharge, said electrode being a rough, stubby compact body presenting to the discharge a solid center and a blunt arcing end throughout which the high heat from the discharge is distributed by the compactly concentrated metal, while the total exposed electrode surface is so correlated with the rated discharge current through the electrode, and with the energy losses therefrom during operation, that the heating of said arcing end by the discharge and the cooling thereof as a result of said energy losses are in balance for a temperature of said arcing end that is of the order of 3000° K.

6. An unactivated refractory metal electrode for self-heating operation in a long-gap high-pressure discharge, said electrode being provided with a current connection and consisting of a coil of refractory metal wire and a refractory metal heat-distributing plug occupying and electrically and thermally interconnecting the adjacent convolutions of said coil, thus forming a rough, stubby compact body presenting to the discharge a blunt arcing end throughout which the high heat is distributed by the compactly concentrated metal, while the total exposed electrode surface is so correlated with the rated discharge current through the electrode, and with the energy losses therefrom during operation, that the heating of said arcing end by the discharge and the cooling thereof as a result of said energy losses are in balance for a temperature of said arcing end that is of the order of 3000° K.

7. An unactivated refractory tungsten electrode for functioning in a long-gap high-pressure discharge, said electrode consisting of a coil of tungsten wire with a current connection directly thereto, and a tungsten heat-distributing plug occupying and electrically and thermally interconnecting the adjacent convolutions of said coil, thus forming a stubby compact body with a blunt arcing end throughout which the high heat is distributed by the compactly concentrated metal there, while the total exposed electrode surface is so correlated with the rated discharge current through the electrode, and with the operating pressure of the discharge atmosphere, that

the heating of said arcing end by the discharge and the cooling thereof by conduction and radiation to and from the rest of the electrode and its current lead and support are in balance for a temperature of said arcing end that is of the order of 3000° K.

8. An unactivated refractory metal electrode member for functioning in a long-gap high-pressure discharge, said electrode member consisting of a coil of refractory metal wire having at its opposite ends convolutions forming, respectively, a lead-wire socket and a close-wound electrode-

body, with a current-carrying portion of widely spaced convolutions interconnecting the socket and electrode-body convolutions, and a refractory metal heat-distributing plug occupying and electrically and thermally interconnecting adjacent electrode body convolutions of said coil, thus forming a squat, compact body with a blunt arcing end throughout which the high heat is distributed by the compactly concentrated metal there.

LYMAN B. JOHNSON.

CERTIFICATE OF CORRECTION.

Patent No. 2,363,581.

November 28, 1944.

LYMAN B. JOHNSON.

It is hereby certified that error appears in the above numbered patent requiring correction as follows: In the drawing, strike out Figure 6 in the lower left-hand corner thereof; and that the said Letters Patent should be read with this correction therein that the same may conform to the record of the case in the Patent Office.

Signed and sealed this 24th day of April, A. D. 1945.

(Seal)

Leslie Frazer
Acting Commissioner of Patents.

the heating of said arcing end by the discharge and the cooling thereof by conduction and radiation to and from the rest of the electrode and its current lead and support are in balance for a temperature of said arcing end that is of the order of 3000° K.

8. An unactivated refractory metal electrode member for functioning in a long-gap high-pressure discharge, said electrode member consisting of a coil of refractory metal wire having at its opposite ends convolutions forming, respectively, a lead-wire socket and a close-wound electrode-

body, with a current-carrying portion of widely spaced convolutions interconnecting the socket and electrode-body convolutions, and a refractory metal heat-distributing plug occupying and electrically and thermally interconnecting adjacent electrode body convolutions of said coil, thus forming a squat, compact body with a blunt arcing end throughout which the high heat is distributed by the compactly concentrated metal there.
